(73) Assignee: **Shenzhen RaySmart Technology Co., Ltd**, Shenzhen (CN)

(57) **CLAIM**
The ornamental design for a microscope universal stand, as shown and described.

(**) Term: **15 Years**

DESCRIPTION

(21) Appl. No.: **29/916,185**

FIG. 1 is a top, front and right side perspective view of a microscope universal stand showing my new design; FIG. 2 is a bottom, rear and left side perspective view thereof;

(22) Filed: **Nov. 8, 2023**

FIG. 3 is a front elevational view thereof;

(51) LOC (14) Cl. **16-06**

FIG. 4 is a rear elevational view thereof;

(52) U.S. Cl.

FIG. 5 is a left side view thereof;

USPC **D16/136; D16/131**

FIG. 6 is a right side view thereof;

(58) **Field of Classification Search**

FIG. 7 is a top plan view thereof;

USPC D16/130, 131, 136

FIG. 8 is a bottom plan view thereof;

CPC G02B 21/00; G02B 21/0008; G02B 21/06

FIG. 9 is an enlarged view of portion 9 in FIG. 1;

See application file for complete search history.

FIG. 10 is an enlarged view of portion 10 in FIG. 1;

(56) **References Cited**

FIG. 11 is an enlarged view of portion 11 in FIG. 2; and, FIG. 12 is a top, front and right side perspective view showing the microscope universal stand in a state of use. The evenly dashed broken lines in the drawings illustrate portions of the microscope universal stand which form no part of the claimed design.

The unevenly dashed broken lines illustrate the boundary of the enlarged views and form no part of the claimed design.
